COMBINED COASTER SET AND HOLDER

Fred Press, White Plains, N.Y., assignor to
Styson, Inc., New York, N.Y.

Filed July 9, 1971, Ser. No. 161,422

Term of patent 14 years

Int. Cl. D7—99

U.S. Cl. D7—45

FIG. 1 is a front view of a combined coaster set and holder showing my new design;

FIG. 2 is a side view thereof;

FIG. 3 is a top view thereof;

FIG. 4 is a rear view thereof; and

FIG. 5 is a perspective view thereof, one of the coasters having been removed from the holder for sake of illustration; it being understood that the coasters are identical in appearance and the rear surfaces thereof are substantially plain and unornamented. The top edges thereof are similar to the bottom edges.

I claim:

The ornamental design for a combined coaster set and holder, substantially as shown and described.
